United States Patent

Des. 236,092
Patented July 29, 1975

236,092

COMPASS

William Macowski, Caldwell, N.J., assignor to Ketcham
& McDougall, Inc., Roseland, N.J.

Filed Jan. 8, 1974, Ser. No. 431,792

Term of patent 14 years

Int. Cl. D10—04

U.S. Cl. D10—68

FIG. 1

FIG. 2

FIG. 3

FIG. 4

FIG. 5

FIG. 6

FIG. 1 is a right front perspective view of a compass showing my new design;

FIG. 2 is a front elevational view thereof;

FIG. 3 is a rear elevational view thereof;

FIG. 4 is a top plan view thereof;

FIG. 5 is a right side elevational view thereof, the left side being a mirror image thereto;

FIG. 6 is a bottom plan view thereof.

I claim:

The ornamental design for a compass, as shown and described.
